PILL OR TABLET MACHINE.

No. 473,432.

Patented Apr. 19, 1892.

UNITED STATES PATENT OFFICE.

WILLARD T. SEARS, OF PHILADELPHIA, PENNSYLVANIA, ASSIGNOR OF ONE-HALF TO WILLIAM M. RHOADS, OF SAME PLACE.

PILL OR TABLET MACHINE.

SPECIFICATION forming part of Letters Patent No. 473,432, dated April 19, 1892.

Application filed December 12, 1891. Serial No. 414,832. (No model.)

To all whom it may concern:

Be it known that I, WILLARD T. SEARS, a citizen of the United States, residing in the city and county of Philadelphia, State of Pennsylvania, have invented a new and useful Improvement in Pill or Tablet Machines, which improvement is fully set forth in the following specification and accompanying drawings.

My invention relates to improvements in pill or tablet machines; and it consists, first, of a hopper for the pill or tablet material movable on the dies, substantially as described.

It further consists of a movable and stationary die having adjustable means, as hereinafter described, for controlling the movements of the same.

It further consists of the combination of parts hereinafter described.

Figure 1 represents a side view of a pill-machine embodying my invention. Fig. 2 represents an end view of the machine shown in Fig. 1, omitting the hopper carrier or arm. Fig. 3 represents a horizontal section on line $\alpha\alpha$, Fig. 1. Fig. 4 represents a vertical section of the holder or hopper. Fig. 5 represents a horizontal sectional view of hopper and inner ends of the dies on the same plane as in Fig. 3, the dies, however, being farther separated than in said figure. Fig. 6 represents a perspective view of a portion of the driving-shaft with the operating-cams thereon. Fig. 7 represents an end view of the hopper carrier or arm with hopper thereon.

Similar letters of reference indicate corresponding parts in the several figures.

Referring to the drawings, A designates a standard or support adapted to be secured to any suitable bed or surface and having journaled in a projecting portion or arm B thereof the driving-shaft C, to which is secured a crank-handle D for rotating the same. Adjustably secured in an arm E of the standard by means of the adjusting-screw F and the clamping-screw G is a stationary die H. A thumb-nut J on the screw F locks the latter in place when adjusted.

K designates a movable die working in bearings in an upwardly-extending portion L of the standard.

The hopper M is secured on a reciprocating bar N by means of a pin P and has the ob-

lique recess Q, leading to a horizontal tubular groove or recess R therein. The inner or adjacent ends of the dies H and K are adapted to fit in said recess R during the movements 55 of the said hopper for a purpose hereinafter explained. To impart reciprocating motion to said bar N, which is supported in the upper part of the portion L of the standard, and thereby to the hopper, one end of the bar is 60 provided with the depending arms T and U, the pair T extending below the center of the shaft C, which is provided with the cams V and W, the former being adapted to engage with the arms T for advancing the hopper in 65 one direction and the latter with the arms U for moving the hopper in the opposite direction.

Secured to the arm E is a spring-arm X in the path of the handle D and adapted when 70 pressed by the latter to pass between the adjacent ends of the dies, so as to remove the finished pill or tablet.

To advance the movable die K in the hopper, one end thereof is engaged by a cam Y 75 on the shaft C, and to move it in an opposite direction a spring Z is employed, the said spring being secured to a projection A' of the standard and provided with an eye E' at one end for its easy manipulation. To adjust the 80 limit of action of the spring, and thereby determine the size of the space between the ends of the die in the hopper, so as to regulate the weight of the tablet, a lever C' is provided, the same being pivoted to the projection A' and having one end bearing against the die K and the other end furnished with an adjustable screw D', working in a socket E' on said lever and having its point adapted to contact with the standard A. 85 90

The operation of the machine is as follows: The material of which the tablet or pill is to be formed is fed in the recess Q, resting on the die K. As the shaft C is rotated the cams V come in contact with the arms T, advancing the hopper, so that the material is carried to the space between the dies, entering the same. The parts W' of the cams W then engage the arms U and move the hopper toward the arm L of the standard until the opening 95 Q in the hopper is moved away from the space between the dies K and H. Part of the cams 100

W are circular, and no further movement of the hopper takes place while the cam Y advances the die K, so as to squeeze or press the material held between the ends of the dies 5 into compact form, when the higher part of the cams W on the shaft C engage the arms U, so as to move the hopper toward the arm L of the standard and from over the space between the ends of the dies, uncovering the 10 tablet. The handle D now comes in contact with the spring X, so as to force it between the ends of the die, removing the finished pill or tablet.

It will be seen that the size of the space between the ends of the dies may be regulated 15 to a certain extent by the adjustment of the stationary die H.

The machine as described is simple in character, of few parts, and not easily liable to get 20 out of repair, and at the same time is efficient in operation.

Having thus described my invention, what I claim as new, and desire to secure by Letters Patent, is—

25 1. A pill or tablet machine having a reciprocating hopper and dies in said hopper, one of said dies being movable in said hopper and the hopper being movable on the dies, said parts being combined substantially as described.

30 2. A pill or tablet machine having a hopper

with an attached bar, mechanism for reciprocating said bar and hopper, a stationary die, and a movable die, said dies fitting in a recess or groove in said hopper and said hopper 35 being movable on said dies, said parts being combined substantially as described.

3. In a pill or tablet machine, a standard, a hopper with a bar having depending arms, and a shaft with cams adapted to engage said 40 arms, so as to impart reciprocating motion to said bar and hopper, said parts being combined substantially as described.

4. In a pill or tablet machine, a standard, a die movable on said standard, a spring secured to said standard and bearing against 45 said die, and means, substantially as described, for controlling the play of said spring, said parts being combined substantially as described.

5. In a pill or tablet machine, a standard, dies having a space between their adjacent ends, a driving-shaft with an operating-handle, and a spring adapted to be engaged by said handle and forced between said dies, said 55 parts being combined substantially as described.

WILLARD T. SEARS.
